UNITED STATES PATENT OFFICE.

WILLIAM J. MAIN, OF WESTPORT, CONNECTICUT, ASSIGNOR TO CHARLES ERETT, OF NEW YORK, N. Y.

COLLAPSIBLE PAPER CUP.

Application filed January 26, 1924, Serial No. 688,672. Renewed March 27, 1928.

My invention relates more particularly to a flat folding or collapsible cup, which is normally flat like an envelope but, when opened, is provided with an integral flat bottom, permitting the cup to stand upright.

I am aware that many varieties of the envelope type of cups are to be found upon the market, and the convenience in packing and cheapness of this type of cup is well recognized, but they have the disadvantage of being without a flat bottom when opened and, therefore, cannot be set down, but must be held in the hand when filled or in use.

Therefore, one object of my improvement is to provide a flat folding cup, with a suitable flat bottom, when the cup is opened, so that when in use, it may be readily set down, and need not be continually held in the hand.

In view of the fact that cups of this character are usually made from a single thickness of paper and have a raw or cut edge for the lip of the cup, which is somewhat inconvenient to drink from, a further object of my improvement is to provide a collapsible cup of this character, with an outward fold at the lip thereof to provide a double thickness, uncut edge for the lip of the cup, thereby avoiding the unpleasantness of having the raw edge of the paper coming in contact with the lips when drinking from the cup.

A further object of my improvement is to provide a single blank, which, when folded by reverse folds on a longitudinal line, will form a saddle fold for the bottom of the cup, and the diagonal corners of the blank are provided with tongues extending laterally and longitudinally, which are adapted to form the double-lip folds when the cup is completed.

In the accompanying drawings, I have shown one form of my improved cup, the blank being shown in Fig. 1; Fig. 2 shows the blank partially folded to form the saddle fold of the bottom; Fig. 3 presents a top plan view of the partially completed cup, as shown in Fig. 2; Fig. 4 shows a further development and folding of the cup, the edges of the blank being secured together; Fig. 5 shows a vertical section on the line 5-5 through the partially completed cup

shown in Fig. 4; Fig. 6 shows the completed cup, in the flat form; Fig. 7 shows an enlarged vertical section (partially distended) 55 of the completed cup on the line 7-7 of Fig. 6; Fig. 8 shows a top plan view of the cup after it is opened; Fig. 9 is a bottom view of the cup when open; Fig. 10 shows the opened cup in side elevation; Fig. 11 is 60 another side elevation of the cup at right angles to the view shown in Fig. 10; and Fig. 12 is a vertical section of the opened cup taken on the line 12-12 of Fig. 10.

Referring to the drawings, the blank 1 from which the cup is formed, is shown in Fig. 1, and comprises an irregular piece of paper or suitable material, preferably punched or cut substantially to the form indicated. The blank thus formed has lateral edges 2 and 3, converging from the ends 4 toward the center of the blank or toward the ends of an imaginary median line, indicated by dotted line A in Fig. 1, extending transversely of the blank at its middle, the halves of the blank being reverse duplicates. The edge 3, however, is preferably located further away from a longitudinal median line 5, so as to provide for a strip overlapping the adjacent edge 2, when the blank is folded to form the 75 cup. A dotted line 6 corresponds in position to the line 2 and indicates the amount of overlap; the line 6 meeting the end of the line representing the edge 2, as readily seen in Fig. 1 of the drawings. When folded, 80 the spaces between the lines 6 and the edges 3 are gummed or covered with cement, as indicated at 7 in Fig. 2 of the drawings. The inner ends (lower ends in the folded cup) 85 of the overlapping strips between the lines 3 and 6, are cut off or notched at 8, down to the middle of the blank or to the intersection of the edge 2 with the line 6, thus preventing more than a double thickness of paper at these points when the cup blank is 90 folded. The blank 1, may be scored along the line 5 and along the lines 9 and 10, the latter of which meet to form a diamond-shaped figure, as indicated in Fig. 1.

The blank 1 is folded in a reverse fold along the scoring lines 5, 9 and 10, the fold along the line 5 from the point where it meets the lines 9 and 10 being opposite to the fold on the portion 5 of the longitudinal

line within the diamond formed by the lines 9 and 10. In other words, the edges 2 and 3 of each half of the blank are folded upward toward each other along the lines 5, 9 and 10, while the portions of the blank between the lines 9 and 10 in the diamond are folded downward on the line 5^a, thus forming a saddle fold, substantially as shown in Fig. 2, where the saddle fold line 5^a is indicated by dotted lines.

As previously stated, it is desirable to provide cups of this character with a double lip and for this purpose, it will be noted that diagonally opposite corners of the blank 1, as shown in Fig. 1, are provided with tabs, tongues or flaps 11 which extends laterally at 12 beyond the edges 3. From the drawings, it will be seen that the tongue 11 extends equally on each side of the dotted line 6, which, in the present instance, represents the center of the flat cup when the blank is folded. The longitudinally extending portions of the tongues 11 are adapted to be folded outward and down, along the dotted line 13, when the cup is completed, as shown in Fig. 6 of the drawings. The overlapping edges of the blank between the edges 3 and the lines 6 are, as previously stated, gummed or covered with suitable cement, as is also the laterally extending portion 12 of the tongue, below the line 13, substantially as shown in Fig. 2 of the drawings. Continuing the folding, the blank is then brought to the position shown in Fig. 3 and the overlapping edges and tongue secured together. This leaves the lower points or tabs 14 of the saddle fold projecting downward, as shown in Figs. 3 and 5, and these are then preferably folded inward along the line 15 to complete the cup in the flat form, as shown in Figs. 6 and 7, the tabs 14 being gummed and secured to the wall of the saddle fold. The folded edges 15 of the saddle fold, will thus determine the bottom of the cup, which, in this case will be substantially square when the cup is opened, as shown in Figs. 8 and 9 of the drawings.

The tongue 11, as previously stated, is folded outwardly and down as shown in Figs. 6 and 7, over the joint between the two opposite ends of the blank, so that, as indicated in Figs. 6 and 10, the tongue 11 will form a lip of double thickness, thereby giving a rounded smooth edge to drink from. The cup, which has been described, may be readily manufactured in its flat or collapsed form, and packed and sold that way. When it is desired to use the cup, it will be found that, by pressure upon the sides of the cup along the fold lines 5-5, as the cup is shown in Fig. 6 of the drawings, the cup will readily open and the saddle fold will be forced down or unfolded to the position shown in Figs. 8 to 12, to form the bottom upon which the cup may stand. The bot-

tom being substantially square and the walls of the cup being without creases or scoring lines, except along the lines 5, it will be seen that the body of the cup will be substantially round, as indicated in Figs. 70 8 and 9, when the cup is opened and more particularly so when it is filled with liquid, thus presenting a pleasing appearance. The overhanging tongue 11 on each side of the cup, as shown in Figs. 10 and 11, forms a 75 rounded uncut edge or lip for the cup, from which to drink. Furthermore, this overhanging lip protects the cup at the seam and does not detract from the appearance of the cup, but on the contrary, adds a pleasing effect to the appearance of the cup, when viewed from above.

It will be understood that while I have shown one form of my improved cup, I do not wish to be limited to the specific details, for obviously, various modifications therein may be made without departing from the spirit and scope of the invention.

I claim:

1. A collapsible paper cup, comprising a single blank of paper, the lateral edges of which taper uniformly from the ends toward the middle, and diagonally opposite corners are provided with laterally and outwardly extending tongues, the cup being formed by reverse folds along a median line longitudinally of the blank, to form a saddle fold at the bottom of the cup, said tapering edges and said tongues being brought into overlapping relation and cemented together, the points of the saddle fold being folded inward and secured to the wall of the saddle to form the bottom of the cup when the latter is open, and the outer parts of said tongues are adapted to fold back to form a double lip over and on each side of the overlapping joint.

2. A collapsible cup, formed of a single blank of paper, having its lateral edges tapering uniformly toward the middle of the blank, the blank being folded along a median line longitudinally and on lines at an angle to the median line, the last mentioned lines of fold forming a diamond through which the longitudinal line of fold extends diagonally, the long way of the diamond, thereby forming a saddle fold with the lateral edges of the blank coming together and overlapping at the middle of the flat folded blank, the diagonally opposite corners of the blank being provided with tongues, extending laterally and longitudinally of the blank, the lateral portions of which, when the blank is folded, extend over the adjacent overlapping wall and are secured thereto and the longitudinally extending portions of the tongues are adapted to be folded back over the edge of the cup to form a double lip therefor.

3. A blank for a collapsible paper cup,

comprising two similar halves on each side of a median transverse line, the edges of each half of the blank tapering inward toward the ends of said transverse line, and tongues 5 projecting laterally and longitudinally from opposite diagonal corners of said blank. in which one of the tapering edges on each half of said blank on opposite sides thereof is wider than the other edge, so that when 10 the blank is folded to form a cup, adjacent edges on the same side of the blank will overlap.

4. The cup blank as claimed in claim 3,

WILLIAM J. MAIN.
